UNITED STATES PATENT OFFICE.

ELIAS A. CLEAVELAND, OF BELVIDERE, ILLINOIS.

SPRING BED-BOTTOM.

SPECIFICATION forming part of Letters Patent No. 252,867, dated January 31, 1882.

Application filed November 28, 1881. (No model.)

To all whom it may concern:

Be it known that I, ELIAS A. CLEAVELAND, a citizen of the United States, residing at Belvidere, in the county of Boone and State of Illinois, have invented a new and useful Improvement in Spring Bed-Bottoms, of which the following is a specification.

My invention relates to improvements in that class of spring mattresses or bed-bottoms known as "invalid-beds," and its objects are to produce a bed having a head portion capable of an upward-inclined adjustment without materially changing the relative position of the mattress-bearing surface of the springs, and to so connect the springs on the outer edge of the spring-bottom, in connection with their diagonal connection, as to limit their independent action. These and the means for accomplishing these results constitute the subject-matter of this specification, and will be hereinafter more fully described.

In the accompanying drawings, Figure 1 is an isometrical representation of my improved bed-bottom, in which the springs are omitted. Fig. 2 is a plan view of a bed embodying my invention, of which Fig. 3 is a side elevation. Fig. 4 is also a side elevation, in which the adjustable head portion is shown in an elevated position. Fig. 5 is a vertical transverse section on dotted line *x*, showing the hinge-joint connection of the adjustable head portion.

In the figures, A represents the outside and B the inner lengthwise beams of the bed-bottom, on which are suitably fixed the transverse slats C, on which the springs are mounted.

At *a* are represented bars suitably slotted lengthwise to receive the pivot-bolts of the adjustable head portion of the bed-bottom.

At D are represented side beams of the adjustable head portion of the bed-bottom. The end portions of these beams at *b* are fitted with an outward-projecting stud or pivot-bolt, *c*, of a proper size to enter the slot in the bars *a* in such a manner as to slide lengthwise therein freely. These bars are placed on the inside of the side beams A of the bed-bottom, at the head end thereof, with their pivot-bolts inserted into the slots of the bars *a*, and the beams resting against their inner surface. These beams are fixed in this relative position by means of the spring-supporting transverse slats E, which

at proper intervals are securely fixed to their upper surface, producing a supplementary adjustable head-frame, having a pivotal connection with the slotted bars *a*, to slide lengthwise 55 therein, and its free head end extends to the head end of the main side beams and capable of being elevated or depressed, as may be required.

At *d* are represented braces, one end of which, as at *e*, is pivoted to the outside of the side beams D of the adjustable head-frame toward their inner end, and the outer ends of these braces *d* are pivoted, as at *h*, to the inside of the head-end portion of the outside beams, A, 65 of the main bottom. By this arrangement it will be seen that if the free end of the adjustable frame is elevated or depressed the pivoted end of the side beams of this frame will slide lengthwise in the slotted bars *a*. 70

At *i* are represented segment ratchet-bars, pivoted at their upper ends, as at *l*, to the outside of the side beams D of the head-frame in recesses prepared to receive them. These segment ratchet-bars are slotted lengthwise, as 75 at *l*, to receive and slide on a stud, *m*, projecting from the outside of the braces *d*. These slotted segment-bars, on the concave edge of their slotted portion, are provided with ratchet-teeth *n*, adapted to engage the stud *m*, projecting from the braces *d*, operating to hold the head-frame in any adjusted position within the limits of the device. The lower ends of these segment-ratchets are connected by means of a transverse rod, *o*, to the center portion of which 80 is fixed a suitable cord, *p*, from which point it extends upward, and is passed through a suitable loop or staple, *r*, in the end slat of the head-frame, and is employed to disconnect or lift and hold the ratchet teeth from engaging the 85 stud *m* to lower the head-frame. 90

At F are represented spiral springs, made in the usual form from suitable material, and are distributed at suitable intervals on the transverse slats C and E, to which their foot-coils 95 are fixed, in this instance by means of suitable staples spanning the foot-wire and driven into the slat.

At H is represented a suitable elastic wire, which is passed through loops *s*, formed by the 100 end of the spring-wire on the upper coil of the spring. This wire H, as will be seen in the draw-

ings, encircles the entire mattress, passing through the loops of the springs and forming the complete outline of the mattress. The springs within the outline-wire employed to produce a complete spring-mattress are suitably connected by diagonal links *t*, which are of spiral-spring form, having their ends by means of suitable loops independently connected to the spiral springs and to the central ring, *u*, producing an independent diagonal elastic connection of the springs *F* and central ring, *u*.

By means of the outline-wire *H*, in connection with the diagonal spiral-spring connecting-links *t*, with the spiral springs *F*, and with the center rings, *u*, I so combine the action of the springs as to produce a superior bed, and by this arrangement of the adjustable head portion by means of its sliding pivotal and its brace supports I produce a bed in which the relative distance between the springs at their bearing-surface will be practically the same in any position of the adjustable head portion within the limits of the devices. In this instance I have only represented a few of the spiral-spring connecting-links *t* in connection with the spiral springs *F* and the rings *u*; but the purpose is to employ them in all the angles instead of the rod-like links shown in the plan view, Fig. 2. In this instance I have employed a segment-ratchet for the purpose of adjusting or varying the angle of the head portion rela-

tively with the main portion of the bed; but for this purpose there may be employed a ratchet-bar placed upon the upper surface of the head-end portion of the outer side beams, and a pawl pivoted to the side beams of the adjustable head portion, in such relative position with the ratchet-bar that its free end will engage the teeth thereof.

40

I claim as my invention—

1. In an invalid-bed, the combination, with the horizontal rails, of a head portion, the side bars of which are provided with studs, the slotted plates secured to the inner sides of the horizontal rails, adapted to receive said studs, and braces and adjusting devices, substantially as set forth.

2. In an invalid-bed, the combination, with the boss *A*, of the head-bars *D*, slotted supporting pieces *a*, braces *d*, having studs *m*, and the pivoted slotted ratchet-bars *i*, substantially as set forth.

3. The combination, with the spiral springs, connected by rings and diagonal spiral springs, of a border or selvage wire surrounding and connecting the upper outer portion of the springs by means of a loop-connection of the end portion of wire from which the spring is formed, substantially as set forth.

ELIAS A. CLEAVELAND.
